UNITED STATES PATENT OFFICE.

ALVIN S. PARTRIDGE, OF RICHMOND HIGHLANDS, WASHINGTON.

LABEL-ATTACHING DEVICE.

Application filed November 4, 1926. Serial No. 146,190.

This invention relates to a label attaching device for use, more especially, with rubber stamps; and its object is the improvement of devices of this character and in the method or means for securing the same to an article without the use of any supplemental means such, for example, as cement or wires.

The invention consists in the novel construction of a label attaching device and in the manner of applying the same, as hereinafter described and claimed.

In the accompanying drawing,

Figure 1 is a perspective view of an embodiment of my invention shown applied to the body element of a rubber stamp. Fig. 2 is a perspective view of the label attaching device, and Fig. 3 is a similar view of a label, shown apart from a stamp. Fig. 4 is a transverse vertical section illustrating the manner now preferred by me for applying the label attaching device to the stamp body; Fig. 5 is a longitudinal vertical section of Fig. 4 and Fig. 6 is an elevational view of the device applying tool illustrated in Figs. 4 and 5.

In carrying out my invention, the article, as the wooden body 10 of a rubber stamp, for example, to which a label is to be applied, is provided in one of its faces, as 12, with a pair of grooves 13. These grooves are parallel with each other the planes of which being at substantially right angles to the body face 12 and longitudinally with respect to the body. 14 represents a strip of paper or cardboard, hereinafter designated as the label, upon which identification matter is marked or printed and is preferably of a width equal to or less than the distance between the grooves 13. The label attaching means, as best shown in Fig. 2, consists of a strip of transparent celluloid or other suitable transparent material.

This celluloid strip is formed to provide a plane central portion 15 between two depending flange elements, each of the flanges being of substantially the shape of a letter V in transverse section.

Such flange provides an inner portion 16 extending downwardly from the strip part 15 to a return bend 17 and thence upwardly in an outer portion 17. A flange portion

17 is of less width than the complementary portion 16, a combined thickness of the two folds of a flange being equal to the width of a groove 13, or nearly so. For use, the label 14 is first seated upon the body face 12 between the groove 13. The attaching device, Fig. 2, is then placed over the label and the folded flanges 16-17 are forced down into the respective grooves 13 whereby the device is coupled to the body for securing the label thereto.

In practice, the inserting of the flange is advantageously accomplished by means of a stuffing tool, see Fig. 6, having at one end a rotary roller 18 which is provided with two thin disk elements 19 which are arranged to track within the interstices between the folds 16 and 17 of the respective flanges.

After locating the attaching device with respect to the label and the body grooves 13, the stuffing tool is employed to have its roller 18 travel over the device and lengthwise thereof in a manner to cause the disk elements of the roller to push the flanges of the device down into the respective body-grooves 13, as will be understood from an inspection of Figs. 4 and 5.

The flanges may be engaged gradually by passing the roller to and fro upon the device. By thus forcing the flange elements into the grooves of the body, the device is joined to the body by the flange elements without the use of any cementitious material or other fastening means.

The provision of the outer flange or flap elements 17 of widths less than the associated flange elements 16 and also less than the depths of the body grooves 13 afford outer edges of the respective flaps which are adapted to take in the opposing wall surfaces of the respective grooves to further prevent the disengagement of the label attaching device.

The construction and manner of applying the device will be understood from the foregoing description.

What I claim is,—

1. The combination with an article having parallel grooves therein, a label, and a label attaching device of substantially the shape of an inverted letter U in transverse section, the side arms of the device being

folded upon themselves and adapted to be forced within said grooves into engaged relation with the article.

2. The combination with an article provided with parallel grooves, of a label device having substantially the shape of an inverted letter **U** in transverse section, the

side arms of the device being folded upon themselves, said folded arms being adapted to be forced into the respective grooves into ¹⁰ engaged relation with the article.

Signed at Seattle, Washington, this 16th day of October, 1926.

ALVIN S. PARTRIDGE.
